UNITED STATES PATENT OFFICE.

WILLIAM JOHN BOUSQUET, OF SPRINGFIELD, MASSACHUSETTS, ASSIGNOR, BY MESNE ASSIGNMENTS, TO SAMUEL SISISKY, OF THOMPSONVILLE, CONNECTICUT.

VENDING MACHINE.

Application filed May 13, 1922. Serial No. 560,646.

To all whom it may concern:

Be it known that I, WILLIAM J. BOUSQUET, a citizen of the United States of America, and a resident of Springfield, in the county of Hampden and State of Massachusetts, have invented a new and useful Vending Machine, of which the following is a specification.

My invention relates to improvements in machines designed for dispensing objects upon the introduction into such machines of coins of predetermined denominations, and consists generally of a supporting frame in a casing, and certain, peculiar, actuating means for the objects dispensed, locking means for said actuating means, coin-operated unlocking means, and operating means for said actuating means, together with such other parts and members as may be necessary or desirable in order to render the machine complete in every respect, all as hereinafter set forth.

The primary object of my invention is to produce a comparatively simple and inexpensive machine which is capable of holding and dispensing a plurality of flat objects, such as paper combs, one at a time, upon the deposit in the machine of a coin of the required denomination or size. As just intimated, this machine is especially designed and adapted for vending paper combs, although it might be used without extensive or material change for vending other objects.

A further object is to provide a machine of this character with easily operated, compact, working parts and members which are comparatively few in number and not liable to get out of order.

Another object is to provide the machine with mechanism which can not, with a single coin, be manipulated for the discharge or delivery of more than one object, however much attempt may be made to manipulate and operate successfully the mechanism after the deposit of such coin. In other words, a coin must be deposited for each object dispensed.

Other objects and advantages will appear in the course of the following description.

I attain the objects and secure the advantages of my invention by the means illustrated in the accompanying drawings, in which—

Figure 1 is a front elevation of a machine

which embodies a practical and preferred form of my invention, the door being open; Fig. 2, a cross section through the main supporting frame for the mechanism of said machine, looking down; Fig. 3, a vertical section through the machine, taken on lines 3—3, looking in the direction of the associated arrow, in Fig. 1, except that the upper portions of the casing and supporting frame are broken off; Fig. 4, a right-hand, side elevation of the machine after removing the corresponding side of the casing; Fig. 5, an enlarged, right-hand, side elevation of the operating mechanism showing the same normally disposed; Fig. 6, a similar elevation showing said mechanism in the act of being operated by or through the medium of a coin, and, Fig. 7, an enlarged detail of the inner terminal portion of the operating rock-shaft, showing the direct supporting means for such shaft.

Similar reference characters designate similar parts throughout the several views.

Paper combs, such as this machine is especially designed to handle, are indicated by the numeral 1.

The machine is provided with an outer casing 2 which is open in front and has a door 4 provided with a suitable lock, with which securely to close such opening. In the top of the casing 2 is a vertical coin slot, as clearly shown at 5 in Fig. 4, wherein said top is cut back far enough to disclose said slot. A delivery orifice 6, for the combs 1, is provided in the door 4.

An operating knob 7 has a shank 8 which is journaled in the right-hand side of the casing 2. With the exception of the shank 8 and its knob 7, the moving parts and members of the mechanism, and also the supporting means for the combs, are attached to or connected with and carried on a frame which fits into the casing 2, and may be removed therefrom in the event repairs are needed, or for any other purpose. This is obviously an important feature of the invention.

The aforesaid frame comprises a bottom plate 9, a back plate 10, a partition plate 11 having a vertical reenforcing strip 12 on the right-hand side and intermediate of the front and back edges thereof, a partition plate 13 parallel with said plate 11, a guide plate 14, and top and bottom spacer bars 15. The bottom 9 is of a size which is

adapted to fit the bottom within the walls and door of the casing 2, and the back 10 is of the same width as said bottom 9 and extends upwardly therefrom to the top of said casing, when the frame is in place in the casing. The back 10 sets forward a short distance from the rear edge of the bottom 9, thus leaving a rearwardly-projecting portion of said bottom, and the under spacer bar 15 is located in the angle formed by said rearwardly projecting portion of said bottom with said back, the upper spacer bar being across the top of said back above said under bar. The back sides 15 of the spacer bars 15 and the back edge of the bottom 9 are all in the same vertical plane. Thus space is provided between the back 10 and the back side of the casing 2 for a pair of lugs 16 which extend rearwardly from said back. The partition 11 forms, with the left-hand side of the casing and a portion of the back 10, a compartment for the combs 1. The reinforcing strip 12 extends downwardly from the top 25 of the partition 11 to within a short distance of the bottom of the same. Secured to the right-hand side of the strip 12 is a vertical coin chute 17, such chute being located directly beneath the coin slot 5. The partition 13 is at the right of the partition 11, and with the right-hand side of the casing and a portion of the back 10 provides a chamber for a coin box 18, such box being receivable on the bottom 9. The greater part of the operating mechanism is located between the partitions 11 and 13. The partition 13 extends upwardly from the bottom 9 to an elevation somewhat above that of the shank 8, and is of the same width as the partition 11, but has the upper, rear portion cut and bent to form the guide 14. The guide 14 extends to the left and upwardly, from the partition 13, into contact at the upper terminal of the forward portion of such guide with the partition 11. The rear portion of the upper edge of the guide 14 does not extend to the left as far as the forward portion of such edge, so that an opening 19, best shown in Fig. 2, is left between said rear portion and the partition 11 for the passage of a gravity latch bar 20. All of the parts and members of this frame are rigidly attached to or connected with each other.

Two horizontal guide rails 21 are provided for the combs 1. These guide rails are turned downwardly at the ends to form feet which rest on the bottom 9 to which latter said feet are secured. The rails 21 are in spaced, parallel relationship, and extend from the back 10 to the vertical plane of the front edge of the bottom 9. The upper surfaces of the rails 21 are slightly above the horizontal plane of the bottom 65 of the inner, constricted portion of the

orifice 6, which orifice is made flaring at the outer end. There is a slot 22 in the bottom of the partition 11, which slot extends from the back 10 forwardly some distance. A slide block 23 is arranged on the bottom 9 between the rails 21, the top of said block being approximately flush with the upper edges of said rails except at the rear end of the block where there is an upwardly-extending lug 24, such lug being slightly less in height than the thickness of any of the combs 1. The back 10 is cut away behind the block 23 to enable said block to be moved back into contact with the lower spacer bar 15. When the block 23 is in its rearmost position, which is the normal position, the lug 24 is beneath the partition 10, as clearly shown in Fig. 3. The block 23 extends above the slot 22. A pin 25 extends to the right from the block 23, beneath the right-hand rail 21 and through the slot 22, into the space between the partitions 11 and 13. The pin 25 is the direct medium for actuating the block 23 forwardly and rearwardly between the front edge of the bottom 9 and the lower spaced bar 15, and the slot 22 is long enough to permit said pin to be moved to the required extent for this purpose. It is understood, of course, that the block 23 is considerably shorter than the distance from the lower bar 15 to the front edge of the bottom 9. The block 23 is the delivery member of the machine.

The combs 1 are stacked on the rails 21, with the lowermost comb resting directly on said rails and on the block 23 in front of the lug 24. It follows, therefore, that when the block 23 is actuated forwardly the lowermost comb is carried with it, and that when said comb is entirely withdrawn from beneath the stack and said block is retracted the combs above drop down onto the rails 21 and said block in readiness for the delivery of the comb that is then at the bottom of said stack. A weight 26 may be placed on top of the combs to insure the downward movement of the same as each bottom comb is withdrawn.

An actuating lever 27, for the block 23, has its upper terminal pivotally connected at 28 with the reinforcing strip 12, and extends downwardly to engage the pin 25, there being a longitudinal slot 29 in said lever to receive the inner terminal of said pin and permit the necessary movement of the parts to take place. The lever 27 is below the lower end of the coin chute 17. Extending forwardly from the lever 27 a short distance below the pivot 28 is an arm 30, and extending rearwardly from said lever a short distance above the lower end thereof is a latch lug 31 which is provided at the rear end on top with a tooth 32. A guide 33 is provided to prevent the lever 27 from 130

springing away from the strip 12. The guide 33 has its forward terminal secured to the partition 11 and extending outwardly and rearwardly from such terminal into contact with the right-hand side of the lever 27. A spring 34 is attached at its forward end to the lever 27, at 35, and at its rear end to the back 10, at 36. The spring 34 tends to actuate the lever 27 rearwardly and to retain 10 said lever in such position, thus causing the block 23, through the medium of the pin 25 to be actuated into its rearmost position, and normally to be retained in such position.

The bar 20 is slidingly arranged in the angle formed by the partition 11 with the back 10, on the right-hand side of said partition, in upper and under guiding and supporting lugs 37 and 38, respectively, which lugs project inwardly from said back. At 20 the base of the bar 20 is a forwardly-extending latch 39 which is provided at the front terminal on the bottom with a tooth 40. The construction and arrangement of parts are such that, when the lever 27 is swung rearwardly on the pivot 28, the tooth 32 is caused to snap into engagement with the tooth 40, and said lever is held and prevented from swinging forwardly and carrying with it the block 23. The openings in the lugs 37 30 and 38 are longer than they are wide, to show which these lugs are shown in section in Fig. 6. This is to enable the bar 20 to move forwardly and rearwardly in the lugs, which movement is required for reasons that 35 will presently appear.

A lever 41 has a pin 42 that projects from both sides at the rear terminal of such lever. The rear terminal of the lever 41 is received between the lugs 16, and the pin 42 is received in the lugs 16. Thus the lever 41 is 40 pivotally connected with the back 10. The lever 41 extends forwardly from the pin 42 with an upward inclination, and said lever is pivotally connected at 43 with the bar 20, 45 the lever being on the right-hand side of said bar, and behind and longitudinally in the same vertical plane with the chute 17. Upon raising the free terminal of the lever 41, said lever swings upwardly on its pivot 42 and 50 carries with it the bar 20, at the same time causing said bar to move rearwardly in the slots or openings in the lugs 37 and 38 and approach the back 10, and upon releasing said lever, said bar descends by gravity and 55 moves forwardly to the front ends of said openings in said lugs. The descent of the bar 20 is checked by the contact of the bar with the aforesaid front edges of the openings in the lugs, because, when such contact 60 takes place, the pivot 43 is above the horizontal plane of the pivot 42. When the bar 20 is in this position the latch 39 is located with its tooth 40 in the path of the tooth 32.

A horizontal, transverse, operating rock- 65 shaft or spindle 44 has its right-hand ter-

minal journaled in the strip 12 and the partition 11, and upset as represented at 55 in said partition to prevent said spindle from being drawn to the right out of engagement therewith. The spindle 44 extends through 70 and is also journaled in the partition 13, and is screw-threaded at the right-hand terminal to engage the inner terminal of the shank 8, which inner terminal is tapped for that purpose. The spindle 44 is not long enough to 75 interfere with the removal of the supporting frame from the casing 2, when the shank 8 is removed from said spindle. The spindle is located between the bottom end of the chute 17 and the pivot 28.

Securely mounted on and secured to the spindle 44 is a coin-receiving rocker 45 provided with a forwardly-extending arm 46. The rocker 45 has a slot 47 therein which opens through the top and rear edge thereof. 80 The back portion of the bottom of the slot 47 is curved downwardly as shown at 48, the rocker being in partial section in Fig. 6 the better to show such downwardly-curved part. The rocker 45 is arranged and located to be oscillated beneath the chute 17 and the adjacent terminal of the lever 41. The longitudinal center of the slot 47 is in the same vertical plane in which are located the longitudinal centers of the chute 17 and the 85 lever 41. A spring 49 has its upper end attached at 50 to the arm 46, and its lower end attached at 51 to the arm 30. The spring 49 is stronger than the spring 34. When the lever 27 is held by the latch 39, 90 the spring 49, acting through the arm 46, normally retains the rocker 45 in the position illustrated in Fig. 5, with the slot 47 located directly beneath the open bottom of the chute 17. The bottom of the chute 17 inclines from the front end upwardly and rearwardly as at 52, to enable a coin in the rocker to be removed from said chute and carried rearwardly when said rocker is tilted rearwardly. A stop pin 53 for the rocker 95 extends to the right from the partition 11 into the path of the arm 46.

A penny, which is the coin of the required denomination for operating this machine, is represented at 54 in Figs. 5 and 6.

Assuming that the supporting frame with the parts and members carried thereby has been slipped into the casing 2, and that the shank 8 has been connected with the spindle 44, and assuming further that a stack of 100 combs has been placed on the rails 21, and that the door 4 has been closed and locked, the complete operation of the machine is described as follows:

The coin 54 is dropped through the coin slot 5 into the chute 17, and passes downwardly through said chute into the rocker 45. The knob 7 is grasped and turned in the direction to tilt the rocker 45 from the position which it occupies in Fig. 5 to that which 125

it occupies in Fig. 6. This operation carries the coin 54 beneath the lever 41 and causes the latter to be swung upwardly on its pivot 42 and thus elevate the rod 20 and withdraw the latch 39 from the engagement with the lug 31. Then the spring 49 acts to swing the lever 27 to the left, against the resiliency of the spring 34, with the result that the block 23 is thrust forward against the door 4, and carries with it the bottom comb 1, the forward terminal portion of which is projected into and beyond the orifice 6—see Fig. 6. The protruding end of this comb is grasped between the thumb and finger and the comb is withdrawn entirely from the machine. Meanwhile the knob 7 is released, and the springs 49 and 34 contract, the first causing the rocker 45 to be tilted into its forward position again with the slot 47 beneath the chute 17 and the second swinging the lever 27 rearwardly again into locking engagement with the latch 39. As the rocker 45 moves into initial position the coin 54, which is grasped between the bottom of the slot 47 and the lever 41, drops downwardly flatwise onto the guide 14 and slides from the latter down into the box 18, the open top of such box being in position to receive the coin as it slides off of the guide. The coin necessarily drops when the rocker 45 is tilted forwardly, because at such time the curved surface 48 of the bottom of the slot 47 rides from beneath said coin and the latter rolls down said surface. It is not possible, therefore, for the coin to be carried forwardly with the rocker beneath the chute. The latch 39 drops as soon as the restraining influence of the coin is removed, so that it is in position to engage the lug 31 as soon as the spring 34 operates to actuate said lug rearwardly. The rearward movement of the lever 27 restores the block 23 to initial position in readiness to thrust forward the next comb.

If the spindle 44 be rocked to tilt the rocker 45 rearwardly, when there is no coin in said rocker, such movement is idle and has no effect on the comb-delivery mechanism, because such mechanism is locked by the latch 39, only the spring 49 being then affected.

In the operation of the mechanism, the coin 54 becomes wedged between the bottom of the slot 47 and the lever 41 in such position and in such a manner that said coin must pass out of the rocker 45, when the latter is actuated forwardly and thus permit the latch 39 to drop into locking position relative to the lever 27, so that it is impossible to obtain more than one comb with a single coin.

The forward movement of the rocker 45 is limited by the upper end of the lever 27 with which the bottom of said rocker comes into contact when tilted forwardly.

The door 4 when closed forms the front side or end of the compartment in which the combs 1 are located. The inner end of the orifice 6 in the door is of a size or proportion to permit the bottom comb to pass out therethrough, while at the same time preventing the comb which is immediately above said first-named comb from entering said orifice.

More or less change in the shape, size, construction, and arrangement of some or all of the parts of this machine may be made without departing from the spirit of my invention or exceeding the scope of what is claimed.

What I claim as my invention, and desire to secure by Letters Patent, is—

1. The combination, in a vending machine, with a sliding delivery member for the objects dispensed, a spring-pressed oscillatory operating member pivotally connected with said delivery member, a longitudinally reciprocating latch for said oscillatory member, a lever pivotally connected with said latch, and a coin chute adapted to deliver a coin in an approximately vertical position at the outlet end of said chute, of means to receive said coin in such position from said chute and with the edge of said coin operate said lever to actuate said latch out of engagement with said oscillatory member.

2. The combination in a vending machine, with a delivery member for the objects dispensed, a spring-pressed oscillatory operating member for said member, a latch for said oscillatory member, and a coin chute adapted to deliver a coin in an approximately vertical position at the outlet end of said chute, of a spring-pressed rocking member in operative relation relative to said chute and said latch, and adapted to receive said coin in such position and with the edge of said coin actuate said latch out of engagement with said oscillatory member.

3. The combination, in a vending machine, with a delivery member for the objects dispensed, a spring-pressed oscillatory operating member for said delivery member, a gravity latch for said operating member, a pivotally-mounted operating arm for said latch, and a coin chute, of a spring-pressed rocker in position to receive a coin from said chute and with such coin to actuate said last-named lever to raise said latch out of engagement with said operating member, when said rocker is actuated against the resiliency of its spring, whereby said operating member is actuated against the resiliency of its spring.

4. The combination, in a vending machine, with supporting means for the objects to be dispensed, a delivery member for such objects, and a coin chute open at the

bottom, of a coin-receiving rocker beneath said chute, an operating lever for said delivery member, a spring connecting said rocker and said lever, a spring arranged to 5 act on said lever against said first-named spring and weaker than the same, locking means for said lever, and means to disengage said locking means from said lever when a coin received by said rocker from 10 said chute is carried away therefrom.

5. The combination, in a vending machine, with supporting rails for the objects to be dispensed, a block arranged to slide between said rails and having a projection 15 to engage the bottom object, a pivotally mounted lever in operative engagement with said slide, a spring arranged to actuate said lever in one direction, and a coin chute in said casing, of gravity latch-mechanism for said lever, a rocker below said chute, said latch mechanism including a member in the path of a coin in said rocker when the latter is moved away from said chute, and a spring, stronger than said first- 20 named spring, arranged normally to retain said rocker in receiving position beneath said chute. *supposed part removed*

6. The combination, in a vending machine, with a sliding member adapted to 30 deliver the bottom object from a stack of objects to be dispensed, a pivotally mounted lever in operative engagement with said member, a spring adapted to actuate said lever in one direction, a gravity latch for 35 said lever, a pivotally mounted lever pivotally connected with said latch, and a chute, of a coin-receiving rocker mounted beneath said chute and adapted to carry a coin therefrom into operative engagement with said 40 second-named lever, whereby said latch is caused to release said first-named lever, and a spring, stronger than the first, connecting said rocker and said first-named lever, and adapted to actuate the latter against 45 the resiliency of its spring.

7. The combination, in a vending machine, with a coin-chute, a gravity latch, and an operating lever for said latch, of a rocker beneath said chute, said rocker having there- 50 in a slot at right angles to the axis of the rocker, the construction and arrangement of parts being such that, when a coin is received in said slot and carried by said rocker into engagement with said lever, which lat- 55 ter is in the path of the edge of said coin, such lever is actuated against the force of gravity exerted thereon by said latch.

8. The combination, in a vending machine, with a coin chute, a gravity latch, and an 60 operating lever for said latch, of a rocker beneath said chute, said rocker having a slot therein a portion of the bottom of which is curved downwardly, the construction and arrangement of parts being such that, when 65 a coin is received in said slot and carried

by said rocker into engagement with said lever, which latter is in the path of such coin, said lever is actuated to raise said latch, and said coin is caused to roll out of said slot by engagement with the operating lever on the return movement of the rocker. 70

9. The combination, in a vending machine, with a coin chute, a gravity latch, and an operating lever for said latch, of a rocker 75 beneath said chute, said rocker having a slot therein to receive a coin from said chute, the construction and arrangement of parts being such that, when a coin is received in said slot and carried by said rocker into engagement with said lever, which latter is in the path of such coin, said lever is actuated to raise said latch, and said coin is caused to roll out of said slot by engagement with the operating lever on the return movement of the rocker, and means to limit the movement of said rocker in both directions. 80

10. The combination, in a vending machine, with a delivery slide, a pivotally mounted lever in operative engagement with said slide, said lever being provided with a latch-engaging member, and a spring adapted to actuate said lever in one direction, of a gravity bar provided with a latch normally in the path of and in engagement with said latch-engaging member, means to support said bar for vertical and to and fro movement, a pivotally mounted lever pivotally connected with said bar, and means to operate said second-named lever, through the medium of a coin, to move said latch out of engagement with said latch-engaging member. 90

11. The combination, in a vending machine, with spaced supporting members for the objects to be vended, a block arranged to slide between said members, and having a projection at the rear end to engage the bottom object, a pivotally mounted lever 100 in operative engagement with said block, and provided with a forwardly extending arm and with a rearwardly extending latch-engaging lug, a spring arranged to actuate said lever rearwardly, a gravity bar mounted to move longitudinally and to and fro, and provided with a latch to engage said lug, a pivotally mounted lever pivotally connected with said bar, and a coin chute, of a suitably journaled spindle provided with a 110

knob, a rocker secured to said spindle beneath said chute, and having a slot opening through the top and rear edges thereof, the rear portion of the bottom of such slot curving downwardly, and said rocker being 120 provided with a forwardly extending arm, and a spring, stronger than the first, connecting said arms, said second-named lever being in the path of a coin in said rocker when the latter is actuated rearwardly, 125 130

whereby said second lever is elevated and carries with it said bar, thus taking said latch out of engagement with said lug, the construction and arrangement of parts being such that, when said rocker, with a coin therein, is tilted forwardly, against the resiliency of its spring, said lever causes said coin to roll down said bottom and out of said slot and said first-named lever is actuated forwardly, against the resiliency of its spring.

12. The combination, in a vending machine, with spaced supporting members for the objects to be vended, a block arranged to slide between said members, and having a projection at the rear end to engage the bottom object, a pivotally mounted lever in operative engagement with said block, and provided with a forwardly extending arm and with a rearwardly extending latch-engaging lug, a spring arranged to actuate said lever rearwardly, a gravity bar mounted to move longitudinally and to and fro, and provided with a latch to engage said lug, a pivotally mounted lever pivotally connected with said bar, and a coin chute, of a suitably journaled spindle provided with a knob, a rocker secured to said spindle beneath said chute, and having a slot opening

through the top and rear edges thereof, the rear portion of the bottom of such slot curving downwardly, and said rocker being provided with a forwardly extending arm, a spring, stronger than the first, connecting said arms, said second-named lever being in the path of a coin in said rocker when the latter is actuated rearwardly, whereby said second lever is elevated and carries with it said bar, thus taking said latch out of engagement with said lug, the construction and arrangement of parts being such that, when said rocker, with a coin therein, is tilted forwardly, against the resiliency of its spring, said lever causes said coin to roll down said bottom and out of said slot and said first-named lever is actuated forwardly, against the resiliency of its spring, and a stop pin to limit the upward movement of said rocker arm and the rearward movement of the rocker, said first-named lever serving as a stop for the forward movement of said rocker.
